UNITED STATES PATENT OFFICE

GEORGE E. RITCHIE, OF HALIFAX, NOVA SCOTIA, CANADA

DESIGN FOR A SUPPORT FOR READING AND WRITING MATTER

Application filed April 14, 1930. Serial No. 35,251. Term of patent 14 years.

To all whom it may concern:

Be it known that I, GEORGE E. RITCHIE, a citizen of Canada, residing at Halifax, in the Province of Nova Scotia, Dominion of Canada, have invented a new, original, and ornamental Design for a Support for Reading and Writing Matter, of which the following is a specification, reference being had to the accompanying drawing, forming a part thereof.

The figure is a perspective view of a support for reading and writing matter, showing my new design.

I claim:

The ornamental design for a support for reading and writing matter, as shown.

GEORGE E. RITCHIE.
